UNITED STATES PATENT OFFICE

LOGAN A. BECKER AND JOHN M. MUNSON, OF LAKWOOD, OHIO, ASSIGNEES TO THE DOBECKMUN COMPANY, OF CLEVELAND, OHIO, A CORPORATION OF OHIO

TUBE FORMING AND REELING MACHINE

Application filed March 22, 1930. Serial No. 438,205.

The present invention relates to the manufacture and reeling of plicated flat tubes from webs or rolls of sheet material and particularly of transparent cellulose sheeting. While not incorporated in the present invention, the reels of transparent tubing are adapted for use with individual packaging machines where the tubing is cut into lengths to receive the articles to be packaged after which the ends of each tube length are sealed. The use of transparent wrappers or containers has become quite extensive as the transparent sheeting protects the article while not interfering with the view thereof, thus giving an added attractiveness to the goods so packaged.

Heretofore, many difficulties have been encountered in attempting to form containers from cellulose sheeting. Such difficulties have been primarily due to the inherent characteristics of the material. The cellulose sheeting employed to make the tubing, such as that sold under the trade name "cellophane", is light in weight and delicate in texture. While it is tough and capable of resisting strain, it is without grain and tears easily in one direction when the tear or cut has once been started. To render sheet cellulose of this type waterproof it is generally coated with a thin layer of thermoplastic material such as paraffin. This coating on the cellulose sheet presents other and new difficulties as to bonding and handling.

It is an object of the invention to overcome the above mentioned difficulties by the provision of an apparatus by which sheet cellulose tubing can be rapidly and economically manufactured directly from rolls or webs of the cellulose sheeting.

A further object of the invention resides in reeling means for coiling the continuously formed tubing in rolls to facilitate the handling and shipping thereof.

The above and other objects of the invention are achieved by the apparatus illustrated in the accompanying drawings and described below, it being understood that the invention is not limited to the specific embodiment thereof shown and described.

In the drawings:

Figure 1 is a longitudinal vertical section through a complete machine embodying the invention;

Figure 2 is a transverse vertical section on line 2-2 of Figure 1 of a portion of the tube forming means;

Figure 3 is a transverse vertical section taken on line 3-3 of Figure 1 of a portion of the tube forming means;

Figure 4 is a transverse vertical section on line 4-4 of Figure 1 of a portion of the tube forming means;

Figure 5 is an enlarged plan view of the reeling means;

Figure 6 is a vertical longitudinal section on line 6-6 of Figure 5;

Figure 7 is an enlarged side elevation of the guide roller latching means shown in plan in Figure 5;

Figure 8 is a sectional view taken on line 8-8 of Figure 6;

Figure 9 is an enlarged view of a portion of Figure 5 illustrating the construction of the removable and stationary reel mandrels;

Figure 10 is a side elevation of a complete reel removed from the machine, and ready for handling or shipment;

Figure 11 is a diametrical section through the reel taken on line 11-11 of Figure 10;

Figure 12 is an enlarged sectional view taken on line 12-12 of Figure 10; and

Figure 13 is a diagrammatic showing of the drive for the various elements of the invention.

The present invention is the combination with the tube forming means of our copending application, Serial No. 406,410, of a reeling device particularly adapted for forming the tubed stock into reels instead of into individual containers as shown in that application.

The structure includes a table 1 to which are fixed extending arms or brackets 2 which, near their ends, removably journal an axle 3 through the agency of pillow blocks 4. A reel 5 of cellulose sheeting, usually wound on a cardboard tube 6, is carried on the axle 3.

A light strap brake 10, having an adjustable weight 11 may be applied to the axle 3 to maintain the proper tension in the drawn

strip and to prevent overrunning of the reel 5.

The web A passes from the reel 5 under a tension roller 12 which is yieldably positioned in arms 13 by springs 13^a and around lower and upper guide rolls 14 and 15.

As the web passes over the guide roll 15 it receives a narrow strip of gum B at or near one edge. The gum is contained in a pot 17 which is pivotally supported at one end upon a shaft 18 and which rests at the other upon an eccentric 19 fixed to a shaft 20. The shaft is adapted to be turned to adjust the eccentric and thus the height of one end of the pot which, pivoting on the center 18, adjusts the gap between a doctor bar on the pot and the roll and regulates the amount of glue which passes onto the roll.

The gum is applied to the web A from the pot 17 through the agency of a gum wheel 28 dipping into the pot and contacting with the web on the roll 15. The shaft journaling the gum wheel 28 is mounted in a bracket 24 which is pivotally carried on the shaft 18. A spring 33 attached to an extension of the bracket 24 serves to hold the gum wheel 28 yieldably against the roll 15, while a latch 35 may be provided to engage with the bracket 24 to hold the gum wheel in an inoperative position.

From the upper guide roll 15 the web A having the narrow strip of gum applied thereto passes below and around a former mandrel 40 on which the tube is folded to form the longitudinally plicated sides thereof. This mandrel includes a central member 41, upper and lower plates 42 and 43 carried on a holder 44 fixed to cross bars 45 and 46. The lower plate 43 is flared rearwardly and upwardly toward the roll 15 as at 43^a to receive the web as it is delivered from the roll.

The upper and lower plates are wider than the central member and these parts are so shaped and proportioned as to conform to the shaping of the tube. The progressive shaping of the mandrel to form the plicated tube is shown by the several cross-sectional views.

As illustrated in Figure 2, vertical fingers 47 are provided to fold the edges of the web A about the former 40. The fingers 47 may be adjustably carried by brackets 48 which in turn are adjustable in relation to a fixed center block 49 by adjusting screws 50 and locking screws 51. Thin horizontal plates 55 mounted on the brackets 48 opposite the central plane of the former are adapted to cooperate with the central member 41 of the former and with the overhanging edges of the upper and lower plates to form folds or pleats 60 at the sides of the web A.

One of the brackets 48 adjustably carries a finger 56 which as shown in Figure 3 is arranged to fold down the ungummed edge of the web A against the former. Carried on the other bracket 48 is a finger 57 which

is adapted to engage the gummed edge of the web as illustrated in Figure 3 to fold it tightly against the previously folded ungummed edge of the web A.

The brackets 48 also adjustably carry arms 58 which rotatably support flanged rollers 59 at their ends. As seen in Figure 4 the freely rotating rollers 59 bear against the former and crease the web about the edge of the upper plate 42.

From the former 40 the web which is in the form of a tube T with bellows-like sides, passes to drawing and pressing rollers 65. Each of the drawing rollers in the form shown comprises a rubber outer portion 65^a and a metal hub 65^b. The rollers are mounted on shafts 66 and 67, the bearings of the upper shaft being slidably carried and yieldable against springs 69. In order to provide means to control the compression between the rolls, thumb screws 70 and lock nuts 71 are provided.

Means for driving the rolls 65 and the various elements of the machine preferably include a main shaft 75, journaled in the frame 1, which carries a pulley 76 at one end thereof while at the other is a hand wheel 77 for feeding or threading purposes. The main shaft 75 drives an auxiliary shaft 78 through the agency of gears 79 and 80. The rolls 65 are in turn driven from the auxiliary shaft 78 by a pinion 81 and gears 82 and 83. The auxiliary shaft 78 also is adapted to drive the guide rolls 14 and 15 by means of miter gears 84 and 85, shaft 86 and miter gears 87 and 88. A series of gears 89, 90 and 91 drive the upper guide roll from the lower guide roll.

A second pair of cooperating rolls 100, exactly similar both as to form and mounting to the rolls 65, are provided to advance the tube T after it leaves the rolls 65.

Leaving the second pair of rolls 100, the tube T is coiled in flat reels, by the reeling means which includes a flat disk 99 fixed to a shaft 102 journaled in a bracket 103 fixed at one side of the table 1. A removable chuck or center 101 is provided to cooperate with the disk 99 and is removably fixed to the shaft 102 by a plurality of locking fingers 104 pivoted at 105 having extensions 104^a which project inwardly and engage in keyways 102^a in the shaft 102. Springs 106 normally urge the ends of the fingers 104 outwardly to clamp the chuck on the shaft. By pressing on the fingers 104 and compressing the springs 106 and thus moving the extensions from the keyway, the operator can quickly remove or replace the chuck 101 from the shaft 102. The extensions are in the form of cams which grip the ends of the shaft and hold the chuck in position, and any tendency of the chuck to move outwardly will tighten the cams.

A form of cardboard or the like upon which the tube T is reeled is received between the

disk 99 and the chuck 101 and preferably includes a flat disk 110^a adapted to lie against the disk 99 and an axial tube which may include the members 110^b and 110^c. The members 110^a, 110^b and 110^c are glued together at 111 for convenience in handling. The disk and chuck are recessed, as shown in Figure 9 to allow the form 110 to properly seat therebetween.

- 5 To drive the shaft 102 and the disk and chuck thereon, a shaft 115 is journaled on the table 1 and is provided with cooperating clutch members 116 and 117, the former being feathered on the shaft and the latter being journaled thereon so that a gear 118 fixed to the member 117 engages with the gear 82 on the shaft of the rolls 65 to drive continually the clutch member 117. The gear 118 also serves to drive gears 119 and 120 on the shafts 20 of the rolls 100. A spring 125, whose compression force is controlled by a pair of adjustable lock nuts 126 carried on a threaded portion 115^a of the shaft 115, serves to force the two clutch members against opposite 25 sides of a friction disc 126 carried between the clutch faces. A thrust collar 127 and a thrust washer 128 are provided on the shaft 115 to prevent longitudinal movement of the clutch member 117 on the shaft 115.
- 30 At the end of the shaft 15 is secured a sprocket wheel 130, which cooperates with a sprocket wheel 131 on the shaft 102 through the agency of a chain 132. An idler sprocket 133 carried on a bell lever 134 is provided 35 to take up the slack in the chain.

In order to hold the disk 110^a tightly against the surface of the disk 99 during the reeling operation, a pair of guide rollers 140 carried on arm 141 and bell lever 142 may 40 be provided. The arm 141 is fixed on a shaft 143 journaled on the table 1 while the bell lever 142 is fixed to a shaft 144 journaled in a bracket 145 on the table. The other arm of the bell lever 142 is pivotally connected by a 45 link 146 to the arm 141 so that the rollers 140 will move toward and from operative position together. At the other end of the shaft 144 is fixed an arm 147 so that a spring 148 secured between the arm 147 and a fixed pin 50 149 will tend to yieldably hold the guide rollers 140 in operating position. An adjustable screw 150 in the arm 147 serves to limit the inward movement of the rollers. A handle 155 fixed to the end of the shaft 143 55 is provided to move the rollers 140 to an inoperative position while a latch 156 cooperating with a notch 155^a in the hub of the handle 155 serves to releasably hold the rollers 140 in the inoperative position.

- 60 In the operation of the device, the axle 3 is lifted off the pillow blocks 4 and a roll of material 5 is placed thereon after which the roll and axle are returned to the machine and the tensioning brake 10 applied. The 65 gum wheel 28 is tipped back to the inopera-

tive position and the web A of the roll is passed under the tension roller 12 and around the upper and lower guide rolls 14 and 15. The web is then worked around the former 40 and the various fingers thereof to the drawing and pressing rolls 65. Now by turning the hand wheel 77 fixed to the shaft 75 the web can be drawn slowly through the machine. It is obvious that the various fingers and wheels of the former 40 can be moved back to some extent to assist in "threading" the web therethrough. Then as the hand wheel 77 is turned to draw the web slowly through the machine the various fingers and wheels of the former can be adjusted to the proper working position and the gum wheel can be brought to the operative position.

The web A drawn from the roll 5 receives a thin strip of gum B from the gum wheel 28 after which it is formed into a plicated tube T by the former. The tube then passes to the rolls 65 and 100 which serve to press the glued portions of the tube firmly together and to crease the tube into a flat 85 shape, as well as drawing the web A continually through the former. The chuck 101 has been previously removed from the shaft 102 and with the guide rollers 140 in the inoperative position, a form 110 has been placed on the shaft, after which the chuck 101 has been replaced and the guide rollers moved to the operative position. The end of the tube T is wrapped about the form 110 and a few turns of the hand wheel 77 serve 90 to start the proper reeling of the tube on the form.

The machine can now be constantly driven by any suitable means through the agency of the pulley 76 attached to the main drive shaft 75.

It will be evident from a study of the gearing of the machine that the angular speed of the reeling means is substantially the same as the angular speed of the drawing rolls 65 and 100. However, the larger circumference of the disk and chuck necessitates the slippage of the clutch 116-117 even when the tube T is only being started to be wound on the form 110. In this manner 110 the tube T as it is wound on the form is constantly under tension, which insures a tight flat reel. After one form 110 is completely filled the chuck 101 is removed from the shaft 102. A second disk 110^d of cardboard 115 or the like, is placed against the side of the reel and a plurality of gummed stickers 160 or like fastening means are applied about the periphery of the reel as illustrated in Figures 10 and 11. In case the stickers 160 are applied when the reel is still against the disk 99, a plurality of radial slots 99^a are 120 provided at the periphery of the disk to allow the stickers to be applied. Stickers may also be applied at the inner periphery of the 130

reel or the additional disc 110^d can be glued to the members 110^b and 110^c. In all cases before the reel can be removed from the disk 99 the guide rollers 140 which hold the disc 110^d against the face of the mandrel 99 must be moved to the retarded or inoperative position by the handle 155 and locked thereat by the latch 156. The tube T is cut and the end on the reel is fastened in any suitable manner such as bending the end of the tube back over one of the fasteners 160 and applying a second fastener as shown at the top of Figure 10.

A second form 110^a, 110^b and 110^c can now be mounted on the shaft 102 between the disk and the chuck and the operation repeated.

As many changes could be made in the construction, it is intended that all matter contained in the above description or shown in the accompanying drawings shall be interpreted as illustrative only and not in a limiting sense. Accordingly, various modifications and applications of the invention, particularly as to the exact web material tubed and to the size or creasing of the tube so formed, can be resorted to without departing from the spirit of the invention or the scope of the appended claims.

What is claimed is:

1. In combination, means to support a roll of web material, means to continuously draw said web material from said roll, means to apply a strip of gum along an edge of said drawn web, means to continuously fold said drawn web into a tube and to simultaneously fold the sides of the tube inwardly to form a plicated tube, said web drawing means also serving to press said plicated tube in a flat form, and reeling means driven by said web drawing means for continuously reeling said flattened tube under tension.

2. In combination, means to support a roll of web material, means to continuously draw said web material from said roll, means to apply a strip of gum along an edge of said drawn web, means to continuously fold said drawn web into a tube and to simultaneously fold the sides of the tube inwardly to form a plicated tube, means to press said plicated tube in a flat form, and reeling means driven by said web drawing means for continuously reeling said flattened tube under tension.

3. In combination, means to support a roll of web material, means to continuously draw said web material from said roll, means to apply a strip of gum along an edge of said drawn web, means to continuously fold said drawn web into a tube and to simultaneously fold the sides of the tube inwardly to form a plicated tube, means to press said plicated tube in a flat form, and reeling means for continuously reeling said flattened tube under tension.

4. In combination, means to support a roll of web material, means to continuously draw

said web material from said roll, means to apply a strip of gum along an edge of said drawn web, means to continuously fold said drawn web into a tube, means to press said tube in a flat form, and reeling means driven by said web drawing means for continuously reeling said flattened tube under tension.

5. In a tube forming and reeling machine, a roll of web material, means to support said roll of web material, means to draw said web material from said roll, means to form said web into a tube, means to press said tube into a flattened form, means for reeling said tube, means for driving said reeling means at a greater speed without load than said web drawing means, and clutch means in said reel driving means to synchronize the speeds so that the tube as it is being reeled is under tension.

6. In a tube forming and reeling machine, a roll of web material, means to support said roll of web material, means to continuously draw said web material from said roll, means to form said web into a plicated tube, means to press said tube into a flattened form, means for reeling said tube, means for continuously driving said reeling means at a greater speed without load than said web drawing means, and clutch means in said reel driving means to synchronize the speeds so that the tube as it is being reeled is under tension.

7. In a tube forming and reeling machine, a roll of web material, means to support said roll of web material, means to draw said web material from said roll, means to form said web into a tube, means to press said tube into a flattened form, means for reeling said tube, means for driving said reeling means, and clutch means in said reel driving means so that the tube as it is being reeled is under tension.

8. In a tube forming and reeling machine, the combination of means to support a roll of web material, means to draw said web material from said roll, means to form said web into a tight flattened tube, means for reeling said tube, said last-named means comprising a stub shaft journaled adjacent said tube forming means, a flat disc fixed on said shaft, a locking core removably fixed to said shaft, a reeling form removably held by the core, and means to drive said shaft from said web drawing means.

9. In a tube forming and reeling machine, the combination of means to support a roll of web material, means to draw said web material from said roll, means to form said web into a tight flattened tube, means for reeling said tube, said last-named means comprising a stub shaft journaled adjacent said tube forming means, a flat disc fixed on said shaft, a locking core removably fixed to said shaft, a reeling form removably held between said mandrels, means to drive said shaft from said web drawing means, and clutch means in

- the shaft driving means whereby the speeds of the drawing means and the reeling means are synchronized and a tension is maintained in the reeled tube.
- 5 10. In a tube forming and reeling machine, the combination of means to support a roll of web material, means to draw said web material from said roll, means to form said web into a tube, means for reeling said tube, said last-named means comprising a stub shaft journaled adjacent said tube forming means, a flat disc fixed on said shaft, a locking core removably fixed to said shaft, a reeling form removably held by the core, and means to drive said shaft.
- 10 15. In a tube forming and reeling machine, the combination of means to support a roll of web material, means to draw said web material from said roll, means to form said web into a tube, means for reeling said tube, said last-named means comprising a stub shaft journaled adjacent said tube forming means, a flat disc fixed on said shaft, a locking core removably fixed to said shaft, a reeling form removably held between said mandrels, means to drive said shaft, and a plurality of auxiliary guide rollers to assist in properly holding the reeling form between the mandrels.
- 20 25. In a tube forming and reeling machine, the combination of means to support a roll of web material, means to draw said web material from said roll, means to form said web into a tube, means for reeling said tube, said last-named means comprising a stub shaft journaled adjacent said tube forming means, a flat disc fixed on said shaft, a locking core removably fixed to said shaft, a reeling form removably held between said mandrels, means to drive said shaft, a plurality of auxiliary guide rollers to assist in properly holding the reeling form between the mandrels, and means to hold said guide rollers in an inoperative position.
- 30 35. In combination, means for continuously forming a tube from web material, means for reeling said tube including a flat disk, a reeling form, means for removably holding the reeling form on the disk, means tending to rotate said disk at a greater speed than the speed of delivery of the tube, and clutch means in said drive whereby a tension is maintained on the tube as it is being reeled.
- 40 45. In combination, means for continuously forming a flat plicated tube from web material, means for reeling said tube including a flat disk, a reeling form, means for removably holding the reeling form on the disk, means tending to rotate said disk at a greater speed than the speed of delivery of the tube, and clutch means in said drive whereby a tension is maintained on the tube as it is being reeled.
- 50 55. In combination, means for continuously forming a flat plicated tube from web material, means for reeling said tube including a flat disk, a reeling form, means for removably holding the reeling form on the disk, means tending to rotate said disk at a greater speed than the speed of delivery of the tube, and clutch means in said drive whereby a tension is maintained on the tube as it is being reeled.
- 60 65. In combination, means for continuously forming a flat plicated tube from web material, means for reeling said tube including a flat disk, a reeling form, means for removably holding the reeling form on the disk, means tending to rotate said disk at a greater speed than the speed of delivery of the tube, and clutch means in said drive whereby a tension is maintained on the tube as it is being reeled.
- 70 75. In a machine for forming a web of material in flat form into a reel of tubular stock, means for folding said web longitudinally and sealing the edges, a reel to receive the same, said reel having means for supporting and holding a core upon which the tubular stock is wound, and a removable disk located against the face of the reel.
- 80 85. In a machine for forming a web of material in flat form into a reel of tubular stock, means for folding the web longitudinally and sealing the edges, means for delivering the web in tubular form, a reel for receiving the same comprising a disk having a hub to receive a removable core, and a surface to support a removable disk at one side of the reel of stock.
- 90 95. LOGAN A. BECKER.
JOHN M. MUNSON.
